INVENTOR
James Moore,
BY Geo. D. Phillips
ATTORNEY

UNITED STATES PATENT OFFICE.

JAMES MOORE, OF STRATFORD, CONNECTICUT.

PENCIL.

Application filed May 20, 1921. Serial No. 471,151.

To all whom it may concern:

Be it known that I, JAMES MOORE, citizen of the United States, residing at Stratford, in the county of Fairfield and State of Connecticut, have invented certain new and useful Improvements in Pencils; and I do hereby declare the following to be a full, clear, and exact description of the invention, such as will enable others skilled in the art to 10 which it appertains to make and use the same.

This invention relates to an improvement in pencils and has for its object to produce a lead propelling pencil of few parts that are 15 easily assembled and efficient in operation.

Referring to the accompanying drawings wherein the same figures and letters of reference indicate like parts throughout the several views:

20 Figure 1 represents a broken view partly in section of the assembled pencil;

Figure 2 is an enlarged broken view partly in section of the forward end of the pencil;

25 Figure 3 is an enlarged detail view of the detachable tip;

Figure 4 is an enlarged detail view of the lead holding tube;

Figure 5 is a detail sectional view of the split anchor ring;

30 Figure 6 is an enlarged detail broken view of the wire coil and its enveloping tube;

Figure 7 is an enlarged broken sectional view of the outer shell or barrel, broken view of the cap, sectional view of the rotatable inner shell, and broken view of the wire coil and its tube;

Figure 8 is an enlarged detail view of the inner rotatable shell, and broken view of the wire coil;

40 Figure 9 is an enlarged detail view of the collar to which the wire coil is anchored, and

Figure 10 is an enlarged broken detail view of the rotatable shell, and Figure 11 is a detail rear elevation of the split anchor 45 ring.

1 represents the outer shell or barrel of the pencil having the tapered end 1^a into which the pencil holding tip 2 is inserted with its outer surface corresponding to the taper of the barrel. The tip has the lead holding channel 3 in alignment with the channel 4 in the lead holding tube 5. 6 is a thread formed on one end of this tube adapted to register with the threaded recess 7 formed in the inner face of the tip 2. 8 is another recess between the channel 3 and recess 7 and is a

trifle smaller than the split end 9 of the tube 5 so as to impart a slight friction on a lead adapted to pass through the tip 2 and tube 5.

The split anchor ring 10 has a taper face 60 corresponding to the interior wall of the tapered end 1^a of the barrel. It has also the axial recesses 11 and 12, the former to receive the inner end of the tube, 5, and the latter to receive the inner end of the tube 13 65 embracing the helical coil 14, which coil is anchored by one end in the recess 15 of the collar 16 secured to the interior of the rotatable shell 17 registering with the interior surface of the barrel 1. The recess 18, Figures 7 and 9, serves as a bearing adapted be journaled on the outer end of the tube 13. The lead propelling follower 19 lies freely within the coil 14 and has the projection 20 extending through the elongated slot 21 of 75 the tube 13.

A portion of the shell is severed to form the spring tongue 22, which spring tongue, when not forcibly compressed, will project above the outer surface of the shell as shown 80 in Figure 10. The outward indentation 23 is formed in the tongue to snap into the annular housing 24 located at the end of the barrel 1 when the shell 17 is assembled within said barrel, and thus maintain the shell 85 17 in workable relation with the barrel. The shell cap 25 is adapted to embrace the outer end of the shell 17 and abut the end of the housing 24 of the barrel, and is held in frictional contact with the shell 17.

90 Assembling the pencil as a whole is a simple and easy operation. Assuming the coil 14 to having been previously secured by one end to its seat 15 in the collar 16, then the tube 13 is passed over the coil and 95 one end seated in the recess 18 and the opposite end inserted in the opening 12 of the split ring 10. The lead holding tube 5 is connected to the tip 2 and said tip inserted into the outer shell or barrel and temporarily 100 held thereagainst while the shell 17, with its before mentioned assembled parts, is inserted in the opposite end of the barrel with the recess 11 of the ring in alignment with the inner end of the tube 5, which end will 105 be entered into such recess before the ring 10 has been compressed by its engagement with the inclined wall *a* of the barrel.

When the shell 17 has been entered far enough to bring the parts 23 and 24 into engagement, the split ring 10 will have been forced against the inclined wall *a* to close

said ring firmly on to the tubes 5 and 13 and thus hold them against any tendency to rotate or move endwise. When the members are thus assembled, the cap 25 is mounted 5 on the shell 17 as shown, and said shell and coil rotated, as before mentioned, by means of said cap to actuate the longitudinal movement of the follower 19 through the medium of the helical coil. The cap, may, however, 10 be assembled to the shell 17 before said shell is entered into the barrel.

Employing a separate tip for the barrel, and securing the lead holding tube thereto, insures accurate alignment of their lead 15 feeding channels 3 and 4.

While I show the coils 14 proportionately larger than the follower 19 it will be understood that they will in practice be reduced so that their interior will form a guiding 20 support for the follower.

The annular indentation 26 is formed near the outer end of the shell 17 to serve as means for securing a rubber tip, not shown, in the mouth of the shell. As this indentation 25 is formed in the shell previous to the formation of the tongue, it is evident that a similar indentation, 26^a, will also appear in the tongue.

Having thus described my invention what 30 I claim is:—

1. In a pencil, the combination of a barrel having a tapered end, an insertible tip corresponding to the tapered end of the barrel, said tip having a lead holding channel and 35 a threaded recess, a tube having a threaded end therefor and a lead holding channel in alignment with the channel of the tip, a split ring having a taper face corresponding to the interior wall of the tapered end of the 40 barrel, said ring having a recess in which the inner end of the tube is seated and forcibly held therein by the grip of the split ring.

2. In a pencil, the combination of a barrel, 45 a rotatable shell mounted therein, a recessed collar secured within the shell, a split ring

having a central recess, a helical coil secured to the collar, a lead propelling follower operatively located within the coil, a tube enveloping the coil, one end of said tube firmly 50 anchored in the recess of the split ring, the opposite end engaging the recess of the collar to serve as a bearing on which the collar is journaled.

3. In a pencil, the combination of a barrel 55 having an annular housing at one end, a shell rotatably mounted in the barrel, said shell having a spring tongue formed therein with an outward indentation adapted to be detachably secured to the housing of the 60 barrel, and a cap embracing the shell and tongue and in frictional engagement with said shell and tongue.

4. A pencil of the character described comprising a barrel having one end tapered 65 and the other end provided with an annular housing, a shell rotatably mounted within the barrel having a spring tongue provided with an indentation adapted to interlock with said housing, a cap embracing the outer 70 end of the shell and in frictional engagement therewith, a collar secured within the shell, a helical coil anchored to the collar, a lead propelling follower located within the coil having means for operatively connecting it 75 therewith, a tube surrounding the coil having means for guiding the follower, said barrel having a tapered end, a split ring within the barrel having a taper face corresponding to the interior taper wall of the 80 barrel, one end of said tube located in said ring and its opposite end serving as a bearing on which the collar is journaled, a tip having a central lead holding channel, a lead holding tube secured to the tip having its 85 inner end located in the split ring and in alignment with the coil tube so that the forcible engagement of the ring with the inclined wall of the barrel will firmly grip both tubes.

In testimony whereof I affix my signature.
JAMES MOORE.
